UNITED STATES PATENT OFFICE

WALTER J. BRIGHTWELL, OF KILGORE, TEXAS

AIR COMPRESSING MACHINE

Application filed August 16, 1930. Serial No. 475,749.

This invention relates to air compressors, and has for one of its objects to improve the general construction of machines of this character and to provide one which shall be adapted to deliver a comparatively large volume of air to a storage tank and maintain it under a high state of compression with the expenditure of comparatively little energy.

To attain the foregoing and other objects, 10 the nature of which will appear as the description proceeds, the invention comprehends the provision of an air compressor which shall embody a plurality of compressing units having reciprocable pistons and dis- 15 charging into the storage tank, and means operable by the source of energy and so connected to the pistons as to cause them to describe their compression strokes successively.

The invention is hereinafter fully de- 20 scribed and claimed and illustrated in the accompanying drawings, wherein:—

Figure 1 is a side elevation of an air compressor constructed in accordance with my invention;

25 Figure 2 is a top plan view thereof with parts in section;

Figure 3 is a detail sectional view on the line 3—3 of Figure 2;

Figure 4 is a fragmentary end elevation;

30 Figure 5 illustrates a portion of the operating mechanism, partly in section and partly in elevation, and

Figure 6 is a detail section view on the line 6—6 of Figure 2.

35 The air compressor comprises a hollow base 1 which is of elongated rectangular formation in plan and elevation and is provided at its rear end with uprights or standards 2. The bottom 3, front end 4 and sides 5 and 5a 40 of the base 1 are formed integrally. The standards 2 are formed integrally with the sides 5 and 5a, and are connected at their front edges by a web 6 which extends from the upper edges of the standards to a plane short

45 of the lower edges thereof. The front ends of the sides 5 and 5a and the lower portions of the standards 2 are reinforced by inwardly directed flanges 7 which are formed integrally with these parts and with the web 6.

50 The front end 4 is provided with an opening

8, and this end and the sides 5 and 5a are provided at their upper edges with inner and integrally connected flanges 9. The sides 5 and 5a are provided near their transverse centers with transversely alined openings 9 and 10, 55 respectively. The standards 2 are provided at their upper ends with bearings 11. The web 6 is provided in its upper end with a recess 12. The base 1 is light, strong and durable, and is adapted to be mounted upon a concrete or other suitable foundation, and is adapted to be secured to the foundation by bolts 13 passing through lugs 14 extending outwardly from the lower edges of the end 4 and sides 5 and 5a. 60

A plurality of compressing units 15, 16, 17 and 18 are carried by the front end portion of the base 1. The compressing units 15 and 16 are located within the base 1, and are secured to the side 5a of the base. The compressing units 17 and 18 are arranged at the outer side of the base 1 and are secured to the wall 5 of the base by bolts 20. The compressing units 15—18 are similar, and each comprises a cylinder 21 fixed to a plate 22 through the medium of which it is secured to the base 1. The cylinders 21 are closed at their rear ends and open at their front ends, and are provided in their heads 23 with intake ports 24 and discharge ports 25. Pistons 26 are reciprocably mounted in the cylinders 21, and are provided with packing rings 27 to establish an air-tight connection between them and the cylinders. 75

The intake ports 24 are under the control of seating valves 28 which are carried by stems 29 extending rearwardly from the cylinders 21. Guide sleeves 30, which extend rearwardly from the cylinder heads 23, are provided for the valve stems 29, and are provided at their front ends with outwardly directed flanges 31 which bear against the cylinder heads and are secured thereto by cap screws 32. The flanges 31 are provided with openings 33 which establish communication between the intake ports 24 and the atmosphere. The guide sleeves 30 carry lubricators 34. The valves 28 are constantly urged in the direction of their closed position by coil springs 35 which surround the valve stems 29 and guide sleeves 30 and which bear at their 80 85 90 95 100

front ends against the flanges 31 and at their rear ends against washers 36 secured to the valve stems by cotter keys 37.

The discharge ports 25 are under the control of inwardly seating valves 38 which are carried by rearwardly directed stems 39. Casings 40 surround the discharge ports 25 and extend rearwardly from the cylinder heads 23. The casings 40 are secured to the cylinder heads 23 through the medium of coupling flanges 41 formed integrally with the cylinder heads. The rear end portions of the casings 40 are radially enlarged, and arranged in these portions thereof are arms 41 which carry guide sleeves 42 for the valve stems 39. The arms 41 rest against the shoulders 43 formed at the juncture of the large and small portions of the casings 40, and are secured in place by bolts 44 and 45, the bolts 45 being hollow and communicating with the interior of the guide sleeves 42 and being provided at their outer ends with lubricators 46. The guide sleeves 42 are arranged in the smaller portions of the casings 40, and extend from the arms 41 to points short of the cylinder heads 23. The valves 38 are constantly urged in the direction of their closed position by coil springs 47 which are mounted upon the guide sleeve 42 and bear at their front ends against the valves 38 and at their rear ends against the arms 41.

The casings 40 of the compressing units 15 and 16 are connected by pipes 48 to a manifold 49, and the casings of the compressing units 17 and 18 are connected by pipes 50 to a manifold 51. The manifold 49 is connected to the manifold 51 by a pipe 52, and the manifold 51 is connected by a pipe 53 to a storage tank 54. The storage tank 54 is provided with a safety valve 55 and with a pressure gauge 56, and it is adapted to be connected to a compressed air motor or the like by a pipe 57.

The pipe 53 is provided with a cut-off valve 58 which is normally opened and normally closed when the compressor is idle. The safety valve 55 is held closed by a spring 58 which is mounted upon the rod 59 of the valve and bears at its lower end against the valve and at its upper end against a bar 60 through which the stem passes. The bar 60 is secured to upright bracket arms 61 by bolts 62. The nuts 63 of the bolts 62 bear against the bar 60 and are adjustable to permit the tension of the spring 58 to be regulated and controlled.

A pivot rod 64 is carried by the openings 9 and 10, and mounted upon the pivot rod at points adjacent their lower ends are levers 65 and 66. The levers 65 and 66 are provided with bosses 67 which surround the rod 64 and which contact with the base sides 5 and 5a to position the lever 65 in alignment with the axial centers of the compressing units 15 and 16 to position the lever 66 in alignment with the axial centers of the compressing units 17 and 18. The levers 65 and 66 are maintained

in the positions as stated by washers 67 which are mounted upon the rod 64 in contact with the levers, and by wedges 68 which pass through the rod and contact with the washers. The lever 65 is connected below the pivot rod 64 with the piston 26 of the compressing unit 15 and above the pivot rod with the piston of the compressing unit 64. The lever 66 is connected below the pivot rod 64 with the piston 26 of the compressing unit 17 and above the piston rod with the piston of the compressing unit 18. The levers 65 and 66 are connected to their respective pistons by rods 69 which are pivotally connected to the pistons, as at 70, and to the levers, as at 71.

A shaft 72 is journaled in the bearings 11, and is in alignment with the lever 65 and a crank 73. The shaft 72 is provided at one end with a disc 74 which carries a wrist pin 75 arranged in alignment with the lever 66. The crank 73 is connected to the lever 65 by a rod 76, and the wrist pin 75 is connected to the lever 66 by a rod 77, the rods being connected to the upper ends of the levers, as at 78. The shaft 72 is provided at its other end with a pulley 79 adapted to be connected by the belt 80 to an engine of any well known or appropriate construction.

The opening 8 in the rear end 4 of the base 1 is provided for the passage of the valve stems 29 and valve casings 40, of the compressing units 15 and 16. The opening 12 of the web 6 provides clearance for the crank 73 of the shaft 72. The connection between the levers 65 and 66 and the pivot rod 64 and the connections between the levers and the rods 69 are lubricated through the medium of grease cups 81. The connection between the rod 76, lever 65 and crank 73, and the connection between the rod 77, lever 66 and wrist pin 75 are lubricated through the medium of grease cups 82. Grease cups 83 and 84 are also provided for lubricating the pistons of the compressing units 15 and 16 and the connections between the pistons and the rods 69.

When the compressor is in operation, the levers 65 and 66 are rocked from the shaft 72, and the rocking of the levers reciprocates the pistons 26 of the compressing units 15-18. During their rearward strokes, the pistons 26 draw air into the cylinders 21 by way of the ports 24, and during their forward strokes, the pistons expel the air from the cylinders by way of the ports 25, the air passing from these ports into the storage tank 54. The crank 73 and wrist pin 75 are angularly related.

In view thereof, and as the pistons of the compressing units 15-18 are connected to the levers 65 and 66 at opposite sides of the pistons of the levers, no two of the pistons will describe their compression strokes at the same time. This insures the smooth operation of the compressor, and, together with the manner in which the pistons are connected to

the shaft, permits a comparatively large volume of air to be highly compressed with the expenditure of comparatively little energy.

It should be understood from the foregoing description, taken in connection with the accompanying drawings, that the compressor is simple, durable and highly efficient, that it may be manufactured and maintained in a high state of efficiency at low cost, and that 10 its parts are compactly arranged and so arranged as to permit easy access to them for adjustment or repairs.

While I have described the principle of the invention, together with the structure which 15 I now consider the preferred embodiment thereof, it is to be understood that the structure shown is merely illustrative and that such changes may be made, when desired, as fall within the scope of the invention as 20 claimed.

I claim:—

An air compressor comprising a hollow base including sides and standards arranged at one end thereof and formed integrally with 25 the sides, upper and lower compressing units arranged within the base at the other end thereof and secured to one of said sides, upper and lower compressing units located outwardly of the base at said last named end 30 thereof and secured to the other of said sides, a vertical lever pivoted near its lower end to and within the base, rods connected to the lever above and below its pivot and connected to said first compressing units, a second vertical lever pivoted near its lower end outwardly of and to the base, rods connected to 35 said second lever above and below the pivot thereof and to said second compressing units, a horizontal shaft journaled upon the standards and provided with angularly related cranks, and rods connected to the cranks and to the upper ends of the levers.

In testimony whereof I hereunto affix my signature.

45 WALTER J. BRIGHTWELL.
